[57] CLAIM

The ornamental design for a vehicle storage box, as
shown and described.

DESCRIPTION

FIG. 1 is a front elevational view of a vehicle storage
box embodying my new design;

FIG. 2 is an end elevational view thereof, the end oppo-
site being substantially a mirror image of the end shown;

FIG. 3 is a top plan view thereof; and

FIG. 4 is a rear elevational view thereof.

The bottom of the vehicle storage box is plain and unor-
namented.

Fig. 2.
